UNITED STATES PATENT OFFICE.

JOHN A. PROFT, OF STRINGTOWN, MISSOURI.

EXTENSION-TABLE.

SPECIFICATION forming part of Letters Patent No. 255,454, dated March 28, 1882.

Application filed September 24, 1881. (Model.)

To all whom it may concern:

Be it known that I, Rev. JOHN A. PROFT, of Stringtown, in the county of Cole and State of Missouri, have invented certain new and useful Improvements in Extension-Tables; and I do hereby declare that the following is a full, clear, and exact description of the invention which will enable others skilled in the art to which it appertains to make and use the same, reference being had to the accompanying drawings, which form a part of this specification.

Figure 1 is a side view of my improved table folded. Fig. 2 is a vertical sectional view of the same. Fig. 3 is a vertical longitudinal sectional view of the table extended. Fig. 4 is a plan view of the bottom of the table. Fig. 5 is a transverse vertical sectional view. Fig. 6 is a detail view, in perspective, of the center piece, and Fig. 7 is a detail view of one of the extension-leaves.

Corresponding parts in the several figures are denoted by like letters of reference.

This invention relates to extension-tables; and it consists in certain improvements in the construction of the same, which will be hereinafter fully described, and particularly pointed out in the claim.

In the drawings hereto annexed, A represents the frame of a table to which my invention has been applied. Said frame, which is supported in the usual manner upon legs B B, has its ends C C connected by two longitudinal braces, D D, provided with cleats E, upon which drawers inserted through openings in the ends of the table-frame are supported.

G G are rollers journaled between the sides of the table-frame and the braces D, and H is a brace secured transversely across the table-frame, as shown. Said last brace H is to be of the same thickness as the table leaf or plate and the extension-leaves, which will be presently described.

The main table leaf or plate I is provided at its side edges with centrally-located downward-projecting strips J J, between which downward-projecting studs K K are located, as shown. The studs K project through slots K² in the brace H, and thus serve, with the

strips J, which fit at the ends of said brace, to 50 prevent the displacement of the main leaf.

The extension-leaves L L are provided with diagonally downward and inward projecting or slanting braces M M, extending between the brace H of the table-frame and the rollers 55 G, upon which latter they rest, so that when the leaves are being extended or folded the friction is greatly diminished by the said rollers, which consequently render the adjustment 60 of the table more convenient.

The brace H is provided with downward-projecting studs K', forming guides for the braces of the extension-leaves.

Upon the sides of the braces M are secured wedges O, which project laterally under the 65 studs K, upon the under side of the main table leaf or plate, as clearly shown in Fig. 5 of the drawings. When the table is folded the plate or leaf I rests upon the center brace, H, and upon the extension-leaves, which are adjusted 70 under the main leaf or plate adjoining brace H, as shown in Fig. 2 of the drawings. When either leaf is pulled out the wedges O of the braces M will bear against the studs K upon the under side of the main leaf, forcing the 75 latter upward and enabling the extension leaf or leaves to be pulled out without frictional contact with the under side of the main leaf, which would be detrimental to the polish and appearance of the extension-leaves. The 80 wedges O are made of such length that when the leaves L are fully extended their outer ends shall strike the ends of the table-frame, thus acting as stops to prevent the leaves from being pulled out, and at the same time 85 their inner ends shall pass from under the studs K, thus permitting the main leaf to drop to a level with the extension-leaves, as shown in Fig. 3.

To fold the table it is only necessary to raise 90 or lift the end or ends of the main leaf until the inner ends of the wedges O may be pushed under the studs K, when the leaf or leaves L may be easily pushed back to their closed position.

Having thus described my invention, I claim and desire to secure by Letters Patent of the United States—

The combination, with a table-frame having the brace H, provided with slots K² and rollers G, arranged as herein shown, of the main leaf I, having studs K projecting downward through the slots K², and the extension-leaves L, having arms M, provided with wedges O, extending under and adapted to bear against the studs K of the main leaf, as herein shown and specified.

In testimony that I claim the foregoing as my own I have hereto affixed my signature in presence of two witnesses.

JOHN A. PROFT.
